EX
OR D 2,256

William S. Bell, Jr. Design for Paper Collar.
Patented Jan'y 30. 1896.
No 2,256

UNITED STATES PATENT OFFICE.

WILLIAM S. BELL, JR., OF BOSTON, MASSACHUSETTS.

DESIGN FOR A PAPER COLLAR.

Specification forming part of Design No. 2,256, dated January 30, 1866.

To all whom it may concern:

Be it known that I, WILLIAM S. BELL, Jr., of Boston, in the county of Suffolk and State of Massachusetts, have invented a new Design for a Paper Collar, of which the following is a full, clear, and exact description, reference being had to the accompanying drawings, making part of this specification, in which—

Figure 1 is a perspective view of my paper collar. Fig. 2 is a section on the line $x x$ of Fig. 1.

My invention consists in embossing the outer fold of a paper collar with a design which shall represent a hem, thus giving a neat and unique appearance to the collar.

To enable others skilled in the art to understand and use my invention, I will proceed to

describe the manner in which I have carried it out.

In the said drawings, A represents the outer fold of a paper collar, which is embossed or stamped, as seen at a , so as to leave a raised portion, b , around the edge of the collar, which represents a hem, and thus gives the collar a neat and finished appearance.

What I claim as my invention, and desire to secure by Letters Patent, is—

The design representing a hem embossed on a paper collar, substantially as shown and described.

W. S. BELL, JR.
